UNITED STATES PATENT OFFICE.

JOHN J. RHODES, OF SOUTH HAMILTON, MASSACHUSETTS, ASSIGNOR OF ONE-HALF
TO FRED M. GORDON, OF SOUTH HAMILTON, MASSACHUSETTS.

HOOK BRACKET.

Application filed June 30, 1924, Serial No. 723,297. Renewed September 1, 1926.

This invention relates to a hook engaging bracket, the general object of the invention being to provide a bracket placed on the roof of a building and designed to receive 5 and support a hook used in suspending a platform or ladder from the roof in painting or otherwise repairing a building.

Another object of the invention is to so form the device that it is attached to the 10 roof and forms part of the same so that it remains in position all the time.

This invention also consists in certain other features of construction and in the combination and arrangement of the several 15 parts, to be hereinafter fully described, illustrated in the accompanying drawings and specifically pointed out in the appended claim.

In describing my invention in detail, 20 reference will be had to the accompanying drawings wherein like characters denote like or corresponding parts throughout the several views, and in which:

Figure 1 is a side view of a building showing 25 the invention in use.

Figure 2 is an elevation of one end of the building.

Figure 3 is an end view of the device.

Figure 4 is a sectional view through a 30 building and one of the brackets.

Figure 5 is a section on line 5—5 of Figure 4.

Figure 6 is a view of the bracket itself.

As shown in these views, the bracket comprises a head 1 and a stem 2, the stem being provided with nail receiving holes 3 and the head being of flat construction on one face with its other face formed with a curved wall 4 which is of the shape of half 35 of a cup which forms with the flat part of the head a recess 5. A hole 6 is provided in the wall 4 at its lower part for draining the recess and a curved lip 7 is formed on the outer part of the wall 4 which provides 40 a groove 8 at the center of the wall at the top thereof. A number of these brackets 45

are adapted to be fastened to the roof A of a building by nails 9 or the like which pass through the holes 3 in the tongue or stem of each device and into portions of the roof. 50 The brackets are put in place when the roof is being shingled and the stem or tongue 2 is covered by the shingles while the head is exposed. Thus the upper ends of hooks 10, which are used to support the cables 11 55 of a stage or platform, can be placed in the recesses 5 of the brackets and thus the hook will be firmly supported on the roof. Portions of the hook will enter the groove 8 so that slipping movement of the hook on the 60 wall 4 is prevented. The hole 6 will prevent water from rain and snow from accumulating in the recesses 5.

It will thus be seen that I have provided 65 permanent means for supporting a platform of a ladder from a roof by the hooks which are attached to said stage or ladder and as the brackets form a part of the roof they can be used over and over again as long as the roof lasts.

It is thought from the foregoing description that the advantages and novel features of my invention will be readily apparent.

I desire it to be understood that I may 70 make changes in the construction and in the combination and arrangement of the several parts, provided that such changes fall within the scope of the appended claim.

What I claim is:

A hook supporting bracket for a roof, so comprising a stem and a head, the stem having holes therein so that it can be nailed to the roof, a semi-cup shaped member connected with the head to form a recess for receiving the head of a hook, the upper edge 85 of said member having a curved recess therein to receive a portion of the stem of the hook to prevent lateral movement thereof and a hole in the bottom of the member for draining the recess formed by said member. 90

In testimony whereof I affix my signature.
JOHN J. RHODES.
